UNITED STATES PATENT OFFICE.

JAMES ERNEST DALEY, OF PORT ANSON, ONTARIO, CANADA.

AUTOMATIC SHAVER.

1,254,990.

Specification of Letters Patent. Patented Jan. 29, 1918.

Application filed June 9, 1916. Serial No. 102,782.

To all whom it may concern:

Be it known that I, JAMES ERNEST DALEY, a subject of the King of Great Britain, residing at Port Anson, in the Province of Ontario and Dominion of Canada, have invented certain new and useful Improvements in Automatic Shavers, of which the following is a specification, reference being had therein to the accompanying drawing.

10 This invention relates to an automatic shaver and has for its principal object the production of a device which is so constructed as to automatically move the razor blade so as to allow the blade to very easily and rapidly shave the face of the user.

Another object of this invention is the production of an automatic shaver which is provided with a simple and efficient means for rapidly reciprocating the connection for 20 the razor, thus permitting the razor blade to very rapidly and automatically shave the face of the user.

Another object of this invention is the production of an automatic shaver wherein 25 adjustable supporting means is provided for the razor blade so that the razor blade will be held so as to reciprocate and also to give the desired length of a stroke when in operation.

30 Another object of this invention is the production of an automatic shaver wherein a housing is provided having a tube extending therefrom so that the housing and tube may very readily and efficiently support the 35 operating elements of the shaver in a compact position so that although the blade may be very readily and rapidly operated for shaving the face of the user the operating elements will be held so as to positively and 40 efficiently operate and also be protected from injury.

With these and other objects in view this invention consists of certain novel combinations, constructions, and arrangements of 45 parts as will be hereinafter fully described and claimed.

In the accompanying drawings:

Figure 1 is a top plan view of the automatic shaver as constructed in accordance 50 with this invention.

Fig. 2 is a horizontal section taken on the

line 2—2 of Fig. 4, looking in the direction of the arrows.

Fig. 3 is a side elevation of the automatic shaver.

Fig. 4 is a central longitudinal section through the automatic shaver.

Fig. 5 is a section taken on the line 5—5 of Fig. 4, looking in the direction of the arrows.

Fig. 6 is a section taken on the line 6—6 of Fig. 4, looking in the direction of the arrows.

Referring to the accompanying drawings by numerals it will be seen that the housing 1 is substantially rectangular and is, of course, hollow. The closure plate 2 is positioned upon the lower side of the housing and is demountably retained in position by means of the screws 3 which pass through the plate 2 and into the walls of the housing 1, whereby the housing and plate will form an inclosed structure for receiving the operating elements of the shaver. The housing 1 is provided with a central opening 4 at one end thereof which registers with the central bore 5 extending through the tube 6. This tube 6 is provided with an integral flange 7 at one end which fits upon the end of the housing 1 so that the tube 6 may be held in a fixed position upon the housing 1 by means of the screws 8 which pass through the flange 7 into the housing 1, as shown in Fig. 4 for this purpose. A short wall 9 is formed within the housing 1 adjacent one end of the housing and depends for a considerable distance although it terminates at a distance from the closure plate so as to not interfere with the free access through the opening 4 formed at one end of the housing 1. As this wall 9 extends entirely across the width of the housing 1, as shown in Fig. 2, it will be readily carried, although it does not extend the entire depth of the housing, as shown in Fig. 4.

The cores 10 are carried in spaced relation by the wall 9 extending from the opposite end of the housing so as to support the electromagnets 11. The flat spring 12 which carries the armature 14 is held by the bolts 13 upon the housing 1 and extends so as to have its branch arms 14' in alignment with

the ends of the cores 10 and the electromagnets 11. The binding post 15 is mounted upon the housing 1, as shown in Fig. 4, although it is insulated therefrom, as shown 5 at 16. At the inner end of this binding post 15 there is carried a spring tongue 17 which is held in a set position by means of the set screw 18. The binding post 19 is grounded upon the housing 1, and these posts 15 and 19 10 are adapted to be supplied with an electric current so that the current will pass through the housing 1 and wall 9 and as a consequence will energize the electromagnets 11. As these electromagnets are energized their 15 magnetism will attract the armature 14 against the tension of the spring tongue 17. It is obvious that in structures of this kind where swinging armatures are employed that as the armature is drawn in one direction by the magnetism of the electromagnets 20 the spring tongue will also be drawn in the same direction for a short distance. As the resistance of the spring tongue becomes greater, however, the spring tongue will 25 finally spring back to its normal position, thus breaking the circuit, and as a consequence, the magnetism of the electromagnets will cease and the spring of the armature 30 will again return the armature to its normal position.

The elongated guard 20 has a flat flange 21 formed thereon and this flat flange 21 rests upon the forward end of the tube 6 and is retained in position by means of the screw 35 22. In this manner it will be seen that the guard will be held in a fixed position upon the outer end of the tube and although this guard is elongated it is substantially semi-circular, in cross-section, as shown in Fig. 4. 27 This guard 20 has a slot 23 formed therein through which the set screw 24 passes so as to carry the elongated flat bar 25. Since the guard is substantially semi-circular in cross-section and the set screw passes 30 through the slot 23 formed therein it will be seen that the bar 25 may be moved in either of two directions and retained in a set position as desired. The blade 26 has a hollow clip 27 which is adapted to receive 35 the blade 28. This clip 27 has the spring strips 29 secured thereto, the opposite ends of the spring clips being secured to the bar 25. Thus, it will be seen that the clip 27 will be efficiently supported although the 40 spring strips 29 will permit the clip to be reciprocated when in operation. The pitman rod 30 which, of course, may be hollow if so desired, has its forward end secured by means of a screw 31 to the blade 26 of the clip 27. This pitman rod 30 extends 45 through the bore 5 of the tube 6 and through the opening 4 of the housing 1 into the housing. The pitman rod further extends beyond the wall 9 and between the magnets 11

so as to have its flat thin end 32 secured by 65 rivets or screws 33, or, in fact, any suitable means, to the armature 14. Therefore, as the armature is being swung the pitman rod 30 will be reciprocated and thus the clip 27 will also be reciprocated, although it will be 70 suspended by the spring strips 29. Upon the reciprocation of the clip 27 it will be seen that the blade 28 will also be reciprocated so as to quickly and efficiently shave the face of the user. The sleeve 34 is 75 removably mounted upon the tube 6 and is retained in a set position by means of the set screw 35. This sleeve 34 has a guard plate 36 formed thereon, which extends in spaced 80 relation with respect to the guard 20 and 85 this guard plate 36 has guard fingers 36' formed upon its forward edge. Thus it will be seen that the guard fingers project at all times beyond the front edge of the blade, although the blade rests thereon, as shown 90 in Figs. 3 and 4. As a consequence, the blade rides evenly upon the fingers, since the fingers slant so as to allow the blade to fit thereon notwithstanding the swinging action 95 of the blade. The fingers are placed upon the face of the user, allowing the beard to project between the fingers and be severed by the blade, although the fingers will protect the face of the user from injury. It will further be noted that the bar 25 may 100 be adjusted by the set screws 26 and as a consequence the stroke of the blade may be limited in this manner.

When this device is in operation the electric current is supplied to the electromagnets so that their energization will cause the armature to be swung or reciprocated and this action will in turn impart reciprocal movement to the pitman 30. The movement which is imparted to the pitman will in turn be imparted to the clip 37, thus causing the blade to be reciprocated and as the blade is reciprocated it will move for a distance beyond the forward portions 105 of the guard and the guard blade so that when the blade is resting upon the face of the user the blade 28 by rapidly reciprocating will come into engagement with the face of the user and thus quickly and efficiently shave the face of the user. It will 110 further be noted that the adjustment of the bar 25 will increase or shorten the stroke of the blade, while the adjustment of the protector blade will allow a longer stroke to be 115 imparted to the face of the user when the 120 device is in operation.

Therefore, it will be seen that a very simple and efficient automatic shaver has been provided which will positively and efficiently shave the face of the user when the pitman is reciprocated, thus saving considerable trouble and expense and will also give a more perfect shave than can possi-

bly be attained by the employment of an ordinary razor. It is, of course, obvious that the device may be made of any suitable material, such for instance as aluminum, with the exception of the spring elements, and the shape or size thereof may be varied according to the desire of the manufacturer without departing from the spirit of the invention. Therefore, it is not desired to limit the construction to the specific form as herein disclosed but to include all such forms of the device as properly come within the scope of the invention as claimed.

What is claimed is:—

15 1. In a device of the class described, the combination of a housing, a tube carried

by and extending beyond said housing, operating means carried within said housing, a pitman connected to said operating means

20 and extending through said tube, an elongated substantially semi-circular guard carried upon said tube, spring strips carried within said guard, a blade supporting clip supported by said strips, whereby said blade

25 supporting clip may be reciprocated, said pitman being connected to said clip so as to rapidly reciprocate the same.

2. In a device of the class described, the combination of a housing, operating means

30 carried within said housing, a tube mounted upon said housing, a guard carried upon said tube, an adjusting means carried upon said guard, spring strips carried by said adjusting means, a blade supporting clip carried

35 by the ends of said strips, said clip being adapted to carry a blade, a pitman connected to said clip and extending through said tube, said pitman being connected to the operating means of said housing so as to

40 be reciprocated for reciprocating said blade supporting clip.

3. In a device of the class described, the combination of a housing, operating means carried within said housing, a tube carried

45 by said housing, a pitman connected to said operating means and extending through said tube, a guard carried upon the forward end of said tube, said guard being provided with a slot, a bar carried by said guard, a

50 set screw extending through said slot and engaging said bar, whereby said bar may be retained in an adjusted set position, spring strips carried by said bar and extending for a considerable distance therebe-

55 yond, a blade supporting clip carried by said strips, said pitman being connected to said blade supporting clip, said blade supporting clip being adapted to carry a blade, whereby said blade may be reciprocated by

60 said pitman, at which time said clip will swing upon said strips, said bar being adapted to move so as to increase or decrease the length of the stroke of said clip.

4. In a device of the class described, the

combination of a housing, operating means carried within said housing, a tube extending from said housing, a pitman connected to said operating means and extending through said tube, a guard carried upon said tube, an adjustable supporting means carried by 70 said guard, a blade carrying clip supported by said adjustable supporting means, said blade carrying clip being adapted to carry a blade, said pitman being connected to said clip, whereby as said pitman is reciprocated reciprocal movement will be imparted to said clip, and an adjustable guard plate carried by said tube and extending adjacent said clip so as to rest upon the face of the user for protecting the same.

5. In a device of the class described, the combination of a housing, operating means carried within said housing, a tube extending

85 from said housing, a pitman connected to said operating means and extending through said tube, a guard carried upon

said tube, an adjustable supporting means carried by said guard, a blade carrying

clip supported by said adjustable supporting means, said blade carrying clip being

adapted to carry a blade, said pitman being connected to said clip, whereby as

said pitman is reciprocated reciprocal movement will be imparted to said clip, a sleeve

slidably mounted upon said tube, means

95 for retaining said sleeve in an adjusted set position, a flat guard plate carried by said

sleeve, whereby said guard plate may be moved to an adjusted set position, said

guard plate extending adjacent said clip, 100 whereby the plate may rest upon the face of the user for protecting the user's face.

6. In a device of the class described, the combination of a guard, spring strips carried within said guard, a blade supporting

105 clip carried by said strips, whereby said blade will be supported, and means for reciprocating said clip.

7. In a device of the class described, the combination of a guard, spring strips carried within said guard, a blade supporting

110 clip carried by said strips, whereby said blade will be supported, means for adjustably regulating the movement of said clip

in one direction, and means for reciprocating said clip.

8. In a device of the class described, the combination of a guard, means for supporting

120 said guard, an adjusting means carried upon said guard, spring strips carried by said adjusting means, a blade-supporting

clip carried by the ends of said strips,

said clip being adapted to carry a blade, and

means carried by said first-mentioned means

for reciprocating said clip, said adjusting

125 means being adapted to regulate the outward movement of said clip.

9. In a device of the class described, the

combination of a guard, means for supporting said guard, said guard being provided with a slot, a bar carried by said guard, a set screw passing through said slot and engaging said bar, thereby holding said bar in an adjusted set position, spring strips carried by said bar, a blade supporting clip

carried by said strips, means for reciprocating said clip, and said bar being adapted to regulate the outward movement of said clip.

In testimony whereof I hereunto affix my signature.

JAMES ERNEST DALEY.
